UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed December 30, 1922. Serial No. 610,031.

My invention relates to mining machines. It has for its object to provide an improved mining machine, and, more particularly, to provide an improved mining machine of the flexibly fed type. A further object of my invention is to provide improved feeding mechanism for such a machine utilizing a feed operating member and a take-up member on the machine whereby the power may be proportioned as desired between these members. A more specific object of my invention is to provide an improved feeding mechanism of the type mentioned having improved means whereby, while the machine may be balanced as desired, the waste of power heretofore involved in braking the take-up member during the cut across the face may be minimized. These and other objects and advantages of my invention will be hereinafter more fully described.

In the accompanying drawings I have shown for purposes of illustration one embodiment which my invention may assume in practice.

In these drawings,—

Fig. 1 is a plan view of a mining machine constructed in accordance with my improvement, portions of the casing being broken away to facilitate illustration.

Fig. 2 is a transverse section on line 2—2 of Fig. 1.

Fig. 3 is a side elevation of the rear end of the advancing side of the machine.

Fig. 4 is a side elevation of the opposite side of the machine.

Fig. 5 is a diagrammatic view showing the machine in different cutting positions while cutting a face.

In this illustrative construction I have shown a mining machine of a well-known type slidable on its bottom on a mine bottom, the same comprising a frame or casing 1 having a cutter bar 2 projecting from one end thereof, herein longitudinally of the frame, and having a cutter chain 3 movable around the cutter bar, the chain being driven by a cutter chain driving sprocket 4 carried within the frame 1 and preferably in rear of a horizontal longitudinally extending motor 5, the power of which is transmitted to this

sprocket 4 and also to a feed operating member 6 and take-up 7 disposed on transverse axes on the opposite sides of the frame. Both these members 6 and 7, which may obviously assume various forms and cooperate with flexible feeding members of different character, are shown herein in the form of chain sprockets adapted to cooperate with a flexible feeding member in the form of a feed chain 8, the ends of which are adapted to be fixed adjacent the opposite ribs with the intermediate portion cooperating with the members 6 and 7. The mechanism for driving the members 6 and 7 and the cutter chain driving sprocket 4 is herein of the variable reaction type described and claimed in my copending application which has now matured into Patent 1,544,071, granted June 30, 1925. As this mechanism per se does not enter into the present case, it will be sufficient herein to say that the one end of the armature shaft of the motor 5 carries a bevel pinion 9 meshing with a larger bevel gear 10 rotatable on an upright axis and connected to the sprocket 4 through variable reaction mechanism 11 normally operative to propel the feed by the reaction of the cutter chain and including a hand wheel adjusted brake band 12 which is adjustable to provide the necessary reaction when the bar is out of the coal. It will further be noted that this mechanism includes a smaller bevel gear 13, disposed around a stud 14 centering the mechanism 11 and sprocket 4, which gear 13 is disposed within the gear 10 and forms the connection of the cutter chain driving mechanism to the feed. Here attention, however, is directed to the fact that while this gear 13 is shown as forming a part of a variable reaction mechanism such a mechanism is not necessary to the broad phases of the present invention so that in considering these broad phases, the details of the variable reaction drive may be disregarded, and the member 13 considered as merely a power driven member rotated by the motor and transmitting the power thereof to the members 6 and 7.

These members 6 and 7 are herein connected to the member 13 through differential mechanism of improved form which I have

termed an unequal differential mechanism, whereby the power transmitted to the members 6 and 7 is differently proportioned in such a predetermined manner as to eliminate the waste of power ordinarily requisite where the same power is transmitted to both members and it is accordingly necessary to absorb certain of the power transmitted to the take-up member through friction mechanism.

More particularly it will be noted that the member 13 engages with a bevel gear 15 in turn rotatable on a transverse axis and herein relative to a transverse shaft 16 on the opposite ends of which the members 6 and 7 are seated. This member 15 at one end rests against a suitable ball bearing 17 seated against a central support 18 carried by the frame above the upper end of the stud 14, the construction being such that the member 15 is freely rotatable about the shaft 16 and the latter is freely rotatable relative to the support 18, a suitable bearing means, for example a sleeve 19, being provided between the shaft and the support. The member 15 also carries thereon a plurality of spur pinions 20 journaled on suitable horizontally disposed radially located studs 21 and meshing both with a pinion 22 comprising teeth carried or formed on the shaft 16 and the teeth of an internal gear 23 housing the pinions, the latter being disposed between the pinion 22 and the internal periphery of the internal gear. As shown, the internal gear is also provided with a sleeve 24 keyed as at 25 to the hub of a friction drum 26 and the sleeve 24 is also connected through a semi-permanent clutch connection 27 with a sleeve 28 on the feed operating member 6, a suitable bearing, as for instance a ball bearing 29, being provided between the sleeve 28 and the drum hub, and suitably positioned on the frame 1. As illustrated, the member 6 is also suitably connected to a reduced portion 30 on the end of the shaft 16 as by a bolt and washer connection 31. Further, it will be noted that the friction drum 26 is acted upon by a suitable brake band 32 operatively connected to a control lever 33 on the top of the frame so that by movement of this lever, the brake band may be adjusted to grip or release the drum 26. Here attention is also directed to the fact that the take-up member 7 is provided with a sleeve 34 similar to the sleeve 28 but longer and keyed as at 35 to the shaft 16, and to the further fact that this sleeve 34 is in turn keyed as at 36 to a friction drum 37 operated upon by a brake band 38, the latter being controllable by a control lever 39 corresponding to the lever 33 controlling the other drum.

Also preferably a bearing 40, similar to the bearing 29, and bolt and washer connection 41, similar to the connection 31, are provided.

While the flexible connections may assume different forms, it will be understood that in all forms a plurality of flexible feeding por-

tions are utilized, one extending in advance of the machine and the other to the receding side thereof. In the form of my invention illustrated wherein a continuous feed chain is provided, the advance flexible feeding portion which is, for example, connected to the left hand rib, extends around a guide 42 on a vertical axis at the front end of the advancing side of the machine and then rearward from this guide under a cooperating guide 43 on a transverse axis and slightly in front of and below the feed operating member 6, the member 8 passing from under this guide 43 over the member 6 and beneath a cooperating guide 44 journaled on a transverse axis below the member 6 and slightly in rear thereof. From this member 44 the member 8 then passes rearward around a guide 45 carried on a vertical axis on the rear end of the frame and transversely across the rear end thereof to a guide 46 disposed at a slight angle to the vertical as illustrated, and then forward along the receding side of the machine over and then under the take-up member 7 and rearward from the under side of that member, over a cooperating guide 47 likewise disposed on a transverse axis and located slightly in rear and below the member 7 and then to another guide 48 disposed on an axis at a slightly more acute angle to the vertical than the axis of the guide 46 and located on the receding side thereof and in a plane below the latter, which guide 48 acts to direct the receding portion of the member 8 to its connection at the right hand rib.

In the operation of my improved construction, it will be apparent that if the portion of the member 8 on the advancing side of the machine is suitably connected to the face as at 49 with the machine disposed as illustrated in full lines in Fig. 5 and the extremity of the receding portion of the member 8 connected to the right hand rib as shown at 50, by suitably rotating the member 6, the advancing portion may be drawn in in such manner as to cause the machine to move from its full line position to its right hand dotted line position as it is sumped in under the face, the advancing portion being shortened and the receding portion being lengthened as illustrated in that figure, this operation being effected when the brake band 38 is applied and brake band 32 slackened up, the feed then being controllable by tightening the band 32 or loosening the band 38. When the machine is in the right hand dotted line position shown in Fig. 5 with the member 8 reset for transverse cut with its jack 49 then at the left hand rib, it will be evident that a transverse movement of the machine will be effected, the advance flexible portion then being drawn in and the receding flexible portion then being paid out. More particularly it will be noted that during this operation, due to the unequal differential mechanism provided,

the power supplied to the feed operating member 6 is materially greater than that supplied to the take-up member 7, the proportion varying with the particular gearing used in the unequal differential mechanism. For example, in the mechanism illustrated approximately a six thousand pound pull may be exerted by the member 6 while the member 7 may exert a pull of only approximately two thousand pounds, the construction thus being such that the power supplied to the members 6 and 7 is proportional to the work required to be performed by the respective members. Obviously if it is desired at any time during this transverse cutting operation to vary the angle of the machine, this may be accomplished by varying the setting of the brake bands in such manner as to cause the machine to be angled to the right or left as desired, while it will be understood that when it is desired to complete the cut and back the machine out of the cut at the left hand rib, this movement may also be obtained by suitable manipulation of the brake bands. Here it will of course be understood that the construction is such that it is possible at all times to maintain the feeding mechanism in the desired balanced relation through the bands 32 and 38, the unequal differential simply eliminating the unnecessary power heretofore supplied to the take up which during crossing the face necessarily had to be absorbed by the take up friction and accordingly wasted. It will also be observed that whenever it is desired to vary the drive of the sprocket 4, this may be readily accomplished through a simultaneous control of the bands 32 and 38. Here of course, it will be understood that the gear ratio of the variable reaction mechanism will be such as to adapt it to use with the unequal differential mechanism.

As a result of my improved construction it will be noted that it is possible to proportion the power supply to the two members 6 and 7 in such manner as to make it entirely unnecessary to waste power during crossing the face by braking the take-up as is necessary where an equal amount of power is connected to both the feed operating member and the take-up member, my improved mechanism taking advantage of the well known fact that the pull on the receding portion is only necessarily a fraction of that necessary on the advancing portion and proportioning the power delivered to these two members in such manner that while the power required to be supplied to each of the two members is always sufficient, there is no necessity for the large waste of power heretofore necessary when the take-up is operated. Attention is further directed to the fact that through the unequal differential mechanism provided, it is made possible by the substitution of different sets of gearing

to vary this proportion as desired to meet different circumstances. It will also be observed that while the mechanism is shown herein as applied only to a left hand machine, i. e. a machine adapted to cut from right to left, the same may be embodied in a right hand machine when desired, the two machines differing only in that the mechanism shown at the right and left hand sides in Fig. 2 shall be transposed.

While I have in this application specifically described one embodiment which my invention may assume in practice, it will be understood that this form of the same is shown for purposes of illustration and that the same may be modified and embodied in various other forms without departing from its spirit or the scope of the appended claims.

What I claim as new and desire to secure by Letters Patent is:

1. The combination with a flexibly fed mining machine having relatively rotatable feed operating and take-up members each adapted to cooperate with flexible feeding means, a shaft constantly rotatable with one of said members, and a power operated unequal differential mechanism between said shaft and the other of said members, said differential mechanism comprising driven members through one of which said shaft is driven and through the other of which said last mentioned member is driven.

2. The combination with a flexibly fed mining machine having relatively rotatable feed operating and take-up members each adapted to cooperate with flexible feeding means, a shaft constantly rotating one of said members, and a power operated unequal differential mechanism between said shaft and the other of said members including an element rotatable with said shaft and an element rotatable relative to said element and with said other member.

3. In combination with a flexibly fed mining machine having relatively rotatable feed operating and take-up members each adapted to cooperate with flexible feeding means, power connections therefor including a shaft constantly rotating one of said members, a pinion rotating with said shaft, meshing pinions rotatable about said shaft, and an internal gear engaging said last mentioned pinions and rotatable with said other member.

4. The combination with a flexibly fed mining machine having relatively rotatable feed operating and take-up members each adapted to cooperate with flexible feeding means, a shaft constantly rotating one of said members, a power operated unequal differential mechanism through which both of said members are driven and arranged between said shaft and the other of said members, and frictional controlling mechanism for said members.

5. The combination with a flexibly fed mining machine having relatively rotatable feed

- operating and take-up members each adapted to cooperate with flexible feeding means, a shaft constantly rotating one of said members, a power operated unequal differential mechanism between said shaft and the other of said members including an element rotatable with said shaft and an element rotatable relative to said element and with said other member, and frictional controlling mechanism for said members.
6. In combination with a flexibly fed mining machine having relatively rotatable feed operating and take-up members each adapted to cooperate with flexible feeding means, power connections therefor including a shaft rotatable with one of said members, a pinion rotatable with said shaft, meshing pinions rotatable about said shaft, an internal gear meshing with said last mentioned pinions and rotatable with said other member, and independent frictional controlling mechanism for each of said members.
7. In combination with a flexibly fed mining machine having relatively rotatable feed operating and take-up members each adapted to cooperate with flexible feeding means, power connections therefor including a shaft rotatable with one of said members and on the ends of which said members are seated, a pinion rotating with said shaft, meshing pinions rotatable about said shaft, an internal gear meshing with said last mentioned pinions and rotatable with said other member, and independent friction mechanism controlling each of said members.
8. The combination in a mining machine of cutting mechanism, feeding mechanism operatively connected to said cutting mechanism and driven by the reaction thereof and including relatively rotatable feed operating and take-up members each adapted to cooperate with flexible feeding means, and means for supplying a greater proportion of power to said feed operating member than to said take-up member while said members rotate at substantially the same angular speed.
9. The combination in a mining machine of cutting mechanism, feeding mechanism operatively connected to said cutting mechanism and driven by the reaction thereof and including relatively rotatable feed operating and take-up members each adapted to cooperate with flexible feeding means, and means for supplying a greater proportion of power to said feed operating member than to said take-up member while said members rotate at substantially the same angular speed and including adjustable controlling means for each of said members.
10. The combination in a mining machine of cutting mechanism, feeding mechanism operatively connected to said cutting mechanism and driven by the reaction thereof and including relatively rotatable feed operating and take-up members each adapted to cooperate with flexible feeding means, means for controlling the reaction of said cutting mechanism, and means for supplying a greater proportion of power to said feed operating member than to said take-up member while said members rotate at substantially the same angular speed and including adjustable controlling means for said members.
11. The combination with a flexibly fed mining machine having feed operating and take-up members respectively cooperating with advance and receding flexible portions and controlling means for each of said members, of power mechanism operative to cause said feed operating member to place a greater tension on said advance portion while said take-up member is under a lesser tension, all while said members rotate at the same angular speed.
12. The combination with a flexibly fed mining machine having relatively rotatable feed operating and take-up members each adapted to cooperate with flexible feeding means and controlling means for each of the same, of power mechanism including an unequal differential through which said members are driven operative to cause each member to exert a different pull in the same direction, said differential having its driven members operatively connected respectively to said feed operating and take-up members.
13. The combination with a flexibly fed mining machine including power driven feed operating and take-up members each adapted to cooperate with flexible feeding means, of means including a differential mechanism through which power is transmitted to said members and automatically operative during the feeding operation to transmit torque in inverse and unequal ratios to said members.
14. The combination with a flexibly fed mining machine including power operated feed operating and take-up members each adapted to cooperate with flexible feeding means, of means including a differential mechanism through which power is transmitted to said members and automatically operative during the feeding operation to transmit torque to said members in inverse ratio and in proportion to the resistance to rotation thereof.
15. The combination with a flexibly fed mining machine including power driven feed operating and take-up members each adapted to cooperate with flexible feeding means, of means including a differential mechanism through which power is transmitted to said members and automatically operative during the feeding operation to transmit a greater torque to said feed operating member than to said take-up member.
16. The combination with a flexibly fed mining machine including feed operating and take-up members each adapted to coop-

erate with flexible feeding means, of power connections therefor including an unequal differential mechanism through which said members are driven during the feeding operation for imparting torque unequally to said members.

17. The combination with a flexibly fed mining machine including feed operating and take-up members each adapted to cooperate with flexible feeding means, of power connections therefor including an unequal differential mechanism through which said members are driven during the feeding operation for automatically supplying more power to said feed operating member than to said take-up member.

18. In a mining machine, a machine frame 20 slideable on its bottom upon the mine bottom, cutting mechanism thereon including a projecting cutter bar, a motor, and feeding means driven by said motor for feeding the machine bodily laterally over the mine bottom including frictionally controlled power driven feed operating and take-up members, flexible feeding means cooperating with said members including advance and receding flexible feeding portions extending in opposite directions from opposite ends of said frame, and means driven by said motor 25 and operatively connected to said members for minimizing waste power except when said take-up member is operated to draw in the flexible portion operated on thereby.

19. In a mining machine, a machine frame 30 slideable on its bottom upon the mine bottom, cutting mechanism thereon including a projecting cutter bar, a motor, and feeding means driven by said motor for feeding the machine bodily laterally over the mine bottom including a feed operating member and a take-up member both adapted to be rotated by power from said motor, flexible feeding means cooperating with said members including advance and receding flexible feeding portions extending in opposite directions from opposite ends of said frame, and mechanism driven by said motor for differentially distributing power to said members and automatically operative to cause said members 45 to exert a different pull on their respective flexible feeding portions to effect feed of the machine in a substantially straight path transversely across the coal face.

20. In a mining machine, a machine frame 50 slideable on its bottom upon the mine bottom, cutting mechanism thereon including a projecting cutter bar, a motor, and feeding means driven by said motor for feeding the machine bodily laterally over the mine bottom including a feed operating member and a take-up member both adapted to be rotated by power from said motor, flexible feeding means cooperating with said members including advance and receding flexible feeding portions extending in opposite directions

from opposite ends of said frame, and mechanism driven by said motor for differentially distributing power to said members and automatically operative to cause said feed operating member to exert a greater and said take-up member a lesser pull on their respective flexible feeding portions to effect feed of the machine in a substantially straight path transversely across the coal face.

21. In a mining machine, a machine frame 75 slideable on its bottom upon the mine bottom, cutting mechanism thereon including a projecting cutter bar, a motor, and feeding means driven by said motor for feeding the machine bodily laterally over the mine bottom including a feed operating member, and a take-up member, and controlling means for each of the same, flexible feeding means cooperating with said members including advance and receding flexible feeding portions extending in opposite directions from opposite ends of said frame, and mechanism driven by said motor including an unequal differential through which said members are driven and operative to cause each member to exert a different pull on their respective flexible feeding portions, said differential having driven elements respectively connected to said feed operating and take-up members.

22. In a mining machine, a machine frame 90 slideable on its bottom upon the mine bottom, cutting mechanism thereon including a projecting cutter bar, a motor, and feeding means driven by said motor for feeding the machine bodily laterally over the mine bottom including a feed operating member, and a take-up member, and controlling means for each of the same, flexible feeding means 100 cooperating with said members including advance and receding flexible feeding portions extending in opposite directions from opposite ends of said frame, and mechanism driven by said motor including an unequal differential through which said members are driven and operative to cause said feed operating member to exert a greater and said take-up member a lesser pull on their respective flexible feeding portions, said differential having driven members respectively connected to said feed operating and take-up members.

23. In a mining machine, a machine frame 110 slideable on its bottom upon the mine bottom, cutting mechanism thereon including a projecting cutter bar, a motor, and feeding means driven by said motor for feeding the machine bodily laterally over the mine bottom including a feed operating member and a take-up member, flexible feeding means 120 cooperating with said members including advance and receding flexible feeding portions extending in opposite directions from opposite ends of said frame, and mechanism driven by said motor including a power 125

driven element and operative connections between said element and said members differentially distributing power to said members and operative automatically to cause each of the latter to exert a different pull on their respective flexible feeding portions.

24. In a mining machine, a machine frame
slidable on its bottom upon the mine bot-
tom, cutting mechanism thereon including
a projecting cutter bar, a motor, and feeding
means driven by said motor for feeding the
machine bodily laterally over the mine bot-
tom including a feed operating member and
a take-up member, flexible feeding means co-
operating with said members including ad-
vance and receding flexible feeding portions
extending in opposite directions from oppo-
site ends of said frame, and mechanism
driven by said motor including a power
driven element and operative connections
between said element and said feed operating
and take-up members including an unequal
differential through which said members are
driven, said differential having different ele-
ments respectively connected to said feed
operating and take-up members.

In testimony whereof I affix my signature.
MORRIS P. HOLMES.
